IMPROVED STEERING APPARATUS.

SAMUEL L. WALKINSHAW, OF BADEN, PENNSYLVANIA.

Letters Patent No. 60,295, dated December 4, 1866.

SPECIFICATION

TO ALL WHOM IT MAY CONCERN:

Be it known that I, SAMUEL L. WALKINSHAW, of Baden, in the county of Beaver, and State of Pennsylvania, have invented a new and useful improvement in Steering Boats and Ships; and I do hereby declare the following to be a full and exact description thereof, reference being had to the accompanying drawings, and to the letters of reference marked thereon.

My invention consists in operating the pilot-wheel of boats or ships by means of steam in connection with the mechanism hereinafter described, or the equivalent of said mechanism.

To enable others skilled in the art to make and use my invention, I will proceed to describe its construction and operation. In the accompanying drawings—

Figure 1 represents a front elevation of my improved apparatus for steering boats and ships.

Figure 2 represents a top view or plan of the same.

Figure 3 represents a section of the driving-gear, which will be hereinafter described.

In the drawings, A represents the frame for supporting the pilot-wheel and its driving-gear. B represents the pilot-wheel, which is furnished with handles, e, and a barrel, x, for the tiller-rope; the wheel and its handles and barrel are constructed in the ordinary manner, and the tiller-rope is placed on the barrel, x, in the usual way. On the face of the pilot-wheel B is secured a bevelled wheel marked C, which gears into a bevelled wheel marked 3, which is secured on the shaft marked g, which is held in the desired position by the bearings marked 7. On the shaft g are two mitre-wheels marked 1 and 2, which gear into the mitre-wheel marked 4, on the shaft D, which is held in the desired position by means of the bearings marked 6. The mitre-wheels 1 and 2 are each furnished with a coniformed face marked i, and are so arranged that they will revolve on the shaft g, and are prevented from sliding back or forward on said shaft by means of suitable collars, or by any other known and suitable device. Between the mitre-wheels 1 and 2, on shaft g, is placed a coupling-sleeve marked 5; this sleeve moves longitudinally on shaft g, and is revolved with the shaft by means of what is termed a "feather," which is shown in figure 3, and is marked 9. The coupling-sleeve is furnished with bell-mouthed ends, which in form and size correspond to the coniform face or projections i of the wheels 1 and 2, and is shifted back and forward on the shaft g, by means of a jointed lever, m, which is furnished with a locking-rod, n, the lower end of which drops into notches, 8, of the disc o of the lever m; this locking-rod is operated in connection with disc, o, and notches, 8, for the purpose of holding the upper part of lever m in a fixed position when changing it from one side to the other of wheel B, as indicated by the dotted lines 10, so that the pilot may change his position from one side of the wheel to the other, which is very desirable, and often absolutely necessary to get the true range of the boat and the channel. Back of the pilot-wheel B and directly opposite to the wheel marked 3, is placed a friction pulley marked f, which is used for the purpose of preventing the wheel c, which is on the face of the wheel B, from becoming unshipped from the wheel 3 by any warping or springing of the wheel B. As the construction and arrangement of the various parts herein described will readily be understood by the skillful mechanic by reference to the accompanying drawings without further description, I will therefore proceed to describe the operation of the several parts, and the relation they bear to each in their operation. The tiller rope is secured on the barrel x in the ordinary manner, and is connected to the rudder of the boat or ship in the usual mode. Steam-power is applied to the crank J, which will revolve the shaft D, which will revolve the wheel 4, which will revolve the wheels 1 and 2, without revolving the shaft g. The wheel B, with its barrel x, is turned to the right or left, as may be desired, by simply shifting the coupling-sleeve 5 against the coniformed faces i of the wheels 1 and 2, which movement of the coupling-sleeve 5 is accomplished by forcing the lever m to the right or left, which movement of the lever must correspond to the motion desired of the wheel B and its barrel x. By bringing the coupling-sleeve midway between the wheels 1 and 2, the wheel B and its barrel x may be revolved in the ordinary manner by operating it with the handles e. The force or power of the wheel 3 on the wheels C and B, will depend on the force with which the coupling-sleeve 5 is brought up against the coniformed faces i of the wheels 1 and 2, for the shaft g is dependent upon the coupling-sleeve 5, feather 9, and the friction of the coupling-sleeve against the coniformed faces i of the wheels 1 and 2 for its motion. It will readily be observed that various arrangements of the several parts herein described may be adopted and the desired result obtained. Therefore I do not confine myself to any one arrangement, form, or size of the parts herein described and set forth.

Having described the nature, construction, and operation of my improvement, what I claim as of my invention, is—

The combination and arrangement of the shaft D and g, wheels, 1, 2, 3, 4, and C, coupling-sleeve 5, jointed lever m, friction-pulley f, and pilot-wheel B; constructed, arranged, and operating in the manner and for the purpose herein described and set forth:

SAMUEL L. WALKINSHAW.
